UNITED STATES PATENT OFFICE

158,039

CARBONATION TESTING DEVICE

Nathan J. Barudin, New Rochelle, N. Y., assignor
of one-half to Metropolitan Tool Works, New
York, N. Y., a partnership, and one-half to
Genevieve E. Parks, Brooklyn, N. Y.

Application March 13, 1948, Serial No. 145,085

Term of patent 3½ years

(Cl. D52—1)

To all whom it may concern:

Be it known, that I, Nathan J. Barudin, a citizen of the United States of America, residing at New Rochelle, county of Westchester and State of New York, have invented a new, original, and ornamental Design for a Carbonation Testing Device, of which the following is a specification, reference being had to the accompanying drawings, forming part thereof.

Fig. 1 is a side elevation of a carbonation testing device embodying my new design;

Fig. 2 is an end elevation of the device as viewed from the left of the device as shown in Fig. 1;

Fig. 3 is an end elevation of the device as viewed from the right of the device as shown in Fig. 1; and

Fig. 4 is a top plan view of the carbonation testing device shown in Fig. 1.

I claim:

The ornamental design for a carbonation testing device, as shown.

NATHAN J. BARUDIN.
